(57) **CLAIM**

The ornamental design for a video teleconferencing center with full screen display, as shown and described.

DESCRIPTION

This application is related to pending U.S. patent application Ser. No. 09/295,618, "Cable Management for a Video Teleconferencing System," by David Smith, et. al., filed on even date herewith; and pending U.S. Design patent application Ser. No. 29/103,717, "Video Teleconferencing Center," by Ly-Huong Thi Pham, Sonja Schiefer and Jerry S. Benson, filed on even date herewith; both of which are incorporated herein by reference.

FIG. 1 is a perspective view of a third embodiment of the new video teleconferencing center with full screen display, including two display monitors each displaying the full screen display and an electronics enclosure;

FIG. 2 is a front view of the third embodiment of the new video teleconferencing center with full screen display;

FIG. 3 is a left side view of the third embodiment of the new video teleconferencing center with full screen display;

FIG. 4 is a right side view of the third embodiment of the new video teleconferencing center with full screen display;

FIG. 5 is a top view of the third embodiment of the new video teleconferencing center with full screen display;

FIG. 6 is a bottom view of the third embodiment of the new video teleconferencing center with full screen display; and,

FIG. 7 is a rear view of the third embodiment of the new video teleconferencing center with full screen display.
